UNITED STATES PATENT OFFICE.

WARREN FISHER, OF NEW ORLEANS, LOUISIANA.

BEARING-BAR FOR GRATES.

1,255,728.

Specification of Letters Patent.

Patented Feb. 5, 1918.

Application filed January 27, 1917. Serial No. 144,931.

To all whom it may concern:

Be it known that I, WARREN FISHER, a citizen of the United States, residing at New Orleans, in the parish of Orleans and State 5 of Louisiana, have invented certain new and useful Improvements in Bearing-Bars for Grates; and I do hereby declare the following to be a full, clear, and exact description of the invention, such as will enable others 10 skilled in the art to which it appertains to make and use the same.

My present invention relates to improvements in bearing bars for grates, and the subject matter of the present application 15 includes a portion of my prior application, Serial No. 130,237, filed November 8, 1916, and entitled "Improvements in grates;" and in addition certain other features which will more fully herein appear.

20 It is one object of my present invention to provide an improved bearing or supporting bar which is mounted in the furnace structure and provided to receive the trunnions of the grate or fire bars, permitting 25 the latter to be freely turned therein when oscillated to shake down the grate.

A further object of the present invention resides in providing an improved bearing or supporting bar which will be simple in 30 construction, and economical of manufacture, and which will admit of readily receiving the trunnions of the fire bars, and as readily providing for their removal when occasion demands.

35 With these and other objects in view the invention consists in the novel details of construction and combinations of parts more fully hereinafter disclosed and particularly pointed out in the claims.

40 In the accompanying drawings forming a part of this application, and in which similar reference symbols indicate corresponding parts in the several views:

Figure 1 is a fragmentary horizontal sectional view of a grate constructed substantially in accordance with my prior application above, and illustrating in top plan the improved bearing or supporting bar.

45 Fig. 2 is an enlarged top plan view of the improved bearing or supporting bar constructed in accordance with my present invention, and illustrating several fire bars in fragmentary dotted plan, as held therein.

50 Fig. 3 is a side elevational view of the bearing bar.

Fig. 4 is an end elevational view thereof.

Fig. 5 is a cross sectional view taken on the line 5—5 of Fig. 3.

Fig. 6 is a similar view taken on the line 6—6 in Fig. 3.

Fig. 7 is a transverse sectional view taken on the line 7—7 in Fig. 3.

Fig. 8 is an enlarged perspective view of one of the improved bearing blocks.

Fig. 9 is a side elevational view of one of 65 the blocks; and

Fig. 10 is an end elevational view of the same.

Referring more particularly to the drawings, and for the present to Fig. 1, 1 designates generally a furnace structure which is preferably of refractory material, incased and bound together by the outer metal covering 2; this covering, however, not being essential, and forming no part of the 70 present invention, as the same is not used in all cases.

The front of the furnace is indicated at 3, in which are the doors 4, leading to the grate, through which the fuel is introduced. 80 At 7 is indicated a bar extending across the front of the furnace, and at 8 is shown my improved bearing or supporting bar, which divides the grate into two or more parts and is so situated as to receive and hold the adjacent trunnions of two separate series of fire-bars. The location of this bearing or supporting bar will also be clear to those 85 skilled in this art from an inspection of my prior application mentioned above. 90

The grate or fire-bars are indicated at 9 as being of any approved or conventional type; such for instance as the similarly numbered bars in my application aforesaid. These bars are provided with staggered 95 teeth or lugs 10 and 11, and are formed solid or hollow; in the latter case, receiving air to aid in the combustion and assist in the draft in the furnace. These grate bars 9 are preferably connected to be oscillated 100 by means of rods 37 and 38, which are the same as those similarly numbered appearing in my other application.

Referring more particularly to Figs. 2 to 10, of the drawings, the improved bearing 105 bar, and associated parts, are formed of a casting 8 having reduced ends 50 and 51, carrying oppositely projecting ribs 52 and 53, respectively, for fitting a suitable support in the furnace provided to receive the 110

same and hold the bearing bar preferably in a central position therein substantially as indicated in Fig. 1. The casting 8 is formed with a web 54, perforated as indicated at 55, and being of reduced thickness as compared with the other parts of the bearing bar. Above the web 54 the bearing bar 8 is provided with a longitudinal series of recesses 56 having sockets 57 in their bases and communicating at one side with bearings 58. These bearings 58 are adapted to receive the trunnions of the grate bars, as indicated in Figs. 1 and 2, where they will be held to support the grate bars for oscillating movement.

As shown to the right in Fig. 3, the recesses 56 receive bearing blocks 60, which appear in Figs. 8, 9, and 10, and which carry projections 61 for entering the sockets 57 in the bearing bar 8. These bearing blocks 60 are formed with curved walls 62 which complete the cylindrical contour with the bearings 58 and fit the trunnions of the fire-bars, all as will be clear from an inspection of the right-hand side of Figs. 2 and 3.

The upper edges of the bearing bar 8 and the blocks 60 are shaped with depressions 63 and 64 for receiving the ashes, and affording a hold for the bed of the fire.

It will, of course, be understood that the trunnions on the fire-bars are first inserted through the recesses 56 in the bearing bar 8, and downwardly therethrough and into the bearings 58, where they have a rotatable snug fit due allowance being made for expansion. Thereupon the bearing blocks 60 are introduced into the recesses 56, they being allowed to descend vertically therein, and when so received they will take up the position shown to the right in Fig. 9 with the projections 61 occupying the sockets 57 and the curved walls 62 embracing the trunnions of the fire-bars. By withdrawing the blocks 60 the trunnions 22 of the fire-bars are readily removed.

In oscillating the fire-bars the shaking arms thereof act as counterweights, permitting the bars to be very easily moved to the vertical position, the thrust in this instance being on the blocks 60 carried by the bearing bar 8. When, however, the fire-bars are oscillated back to the horizontal position, the lugs 10 and 11 will be moved through their "cutting" stroke, breaking up the clinkers 55 and ashes and forcing the same into the ash pit; and during this return movement the thrust transmitted through the journals 22 will be received not on the removable bearing blocks 60, but on the solid bearings 58 in the supporting bar 8.

In the opposite walls of each recess 56 are provided slots 100 and 103, which are formed with beveled bottoms 110 and 111, which incline downwardly toward the interior of the recesses so as to deliver any ashes there-

to that may have crept in the slots 100 or 103. On the bearing blocks 60 there are formed lugs 101 and 102, which, when the bearing blocks are fitted into the recesses 56, are received into the slots 100 and 103, thus guiding the blocks 60 into the recesses, and when in place, preventing the blocks from being laterally displaced. The bottom edges of these lugs 101 and 102 are preferably formed straight so as to leave the inclined bottoms 110 and 111 of the slots free, and not to interfere with the movement of the ashes thereover.

Adjoining and communicating with the recesses 56 are cut-away portions 104, which are disposed opposite the bearings 58, and beneath which are inclined surfaces 105. When in position, as shown to the right in Fig. 3, the left vertical walls of the bearing blocks 60 extend slightly into the cut-away portions 104 and above the inclined surfaces 105, whereby to receive any ashes descending from the beveled bottoms 110 of the slots 100, which will pass to the cut-away portions 104, and on to the surfaces 105 by 90 which they will be deflected out of and away from the bearing bar and into the ash pit beneath.

The bearing blocks, as more particularly shown in Figs. 8 and 9, are provided with substantially central and elongated openings 112, which afford a greater radiating surface with the result of maintaining the blocks at a relatively lower temperature than when solid, and for the purpose of reducing 100 the quantity of metal and the weight of the block.

The curved walls 62 of the bearing block 60 are preferably supplied with flanges 106, which extend beyond the bearing bar in a 105 manner similar to the flanges of the bearings 58, and afford an increased bearing surface for the trunnions of the fire-bars 9. Any ashes that may find their way between the bearing block 60 and the bearing bar, as shown at 109, will fall into the bearings 58 and will be worked out through the sides of said bearings by the action of the fire-bar trunnions when oscillated in shaking down the grate.

The dimensions of the bearing bar 8, as well as the dimensions of the other parts, may be varied to suit specific requirements in each case, and it will be obvious that various modifications might be made in the herein described device and in the construction, combination, and arrangement of parts which could be used without departing from the spirit of my invention.

Having thus described my invention, what I claim and desire to secure by Letters Patent of the United States is:

1. A supporting bar having a recess, a bearing adjoining said recess at one end, and a cut-away portion leading from the 130

bottom of said recess opposite said bearing and extending beneath the wall of the recess, said cut-away portion provided with inclined surfaces, and a bearing block fitting in said recess and extending partially into said cut-away portion, substantially as described.

5 2. A supporting bar having recesses, bearings, cut-away portions, inclined surfaces

beneath said cut-away portions, and slots formed with beveled bottoms, and bearing 10 blocks fitting said recesses and extending some distance into said cut-away portions, said blocks having lugs received into said slots, substantially as described.

In testimony whereof, I affix my signature. 15
WARREN FISHER.

Copies of this patent may be obtained for five cents each, by addressing the "Commissioner of Patents, Washington, D. C."
